UNITED STATES PATENT OFFICE

JOSEPH LAMBERG JAMESON AND CHARLES JOHN FISHER, OF SURREY, ENGLAND

INTERNAL-COMBUSTION ENGINE

Application filed September 15, 1927, Serial No. 219,757, and in Great Britain April 11, 1927.

This invention comprises improvements in or relating to internal-combustion engines of the type which comprises a working cylinder, a main piston therein, a movable head-piston 5 which is caused to approach the main piston closely at the end of the exhaust stroke and a sleeve-valve which is interposed between the cylinder bore and the main piston and head-piston and carries ports to control inlet and 10 exhaust-ports located in the cylinder wall.

It is an object of the invention to provide an improved engine of this type.

The invention comprises in an internal combustion engine of the type described the 15 combination with a ported sleeve-valve of a cylinder provided with inlet and exhaust-ports situated close together and separated by a "land" of small dimensions in the direction of travel of the sleeve-valve and means to 20 actuate the sleeve-valve so that the port therein alternately opens the inlet and exhaust-ports in the cylinder wall. Thus the same port in the sleeve serves for both inlet and exhaust.

25 Preferably an obturating lip, for example formed by the inner edge of the head-piston (as by a junk-ring), carried upon the head-piston within the sleeve-valve, is so located as to shut off the port in the sleeve from the 30 working space between the pistons, when the parts are in a position which, when the engine is running, will involve high pressure in the cylinder. In this way, the pressure is confined between the main piston, the head-piston 35 and the inner walls of the sleeve-valve so that leakage through the sleeve-ports along the cylinder wall is obviated. Moreover, by employing an obturating lip in this way, it is found possible so to time the parts that the 40 inlet and exhaust-ports can be kept open for the most desirable periods without employing a double sleeve so that the construction of the engine is simplified.

45 The inlet and exhaust-ports may extend around the whole periphery of the cylinder-wall, that is to say, the ports may be continuous around the periphery or may be virtually continuous, being subdivided by transverse ribs at intervals.

50 The sleeve-valve may be cam-operated and

in this case a wide variety of movements may suffice to open or close the ports at the proper times. Preferably however, means are provided for so reciprocating the sleeve-valve (when the engine is working) once for each 55 two reciprocations of the main piston that the sleeve-valve port passes toward the exhaust side of the "land" between the inlet and exhaust-ports while the obturating-lip on the head-piston is in a position which shuts off 60 the port in the sleeve from the working-space between the pistons so that the exhaust-port may be opened immediately the obturating-lip uncovers the port in the sleeve-valve. This movement may be effected by a simple 65 form of cam or it is possible to effect it by suitable timing from an eccentric or crank.

The invention will now be further described with reference to the accompanying drawings which illustrate specific constructions by way 70 of example.

Referring to the drawings:—

Figure 1 is a vertical elevation, mainly in section, of one construction;

Figure 2 is a diagram illustrating a suitable timing and movement for the sleeve-valve;

Figure 3 is a vertical section through the head end of the cylinder of a second construction of multi-cylinder engine, the section being taken along the line 3—3 of Figure 4;

Figure 4 is a plan of the interior of the cam-shaft chamber with the head cover removed, showing the parts at the level of the line 4—4 of Figure 3;

Figure 5 is a diagram showing the essential features of a cross-section upon the line 5—5 of Figure 3, looking upwardly with the pistons and sleeve-valves removed;

Figures 6 and 7 are details of a modified 90 form of sleeve-valve actuating-rocker.

Like reference characters indicate like parts throughout the drawings.

Referring first to Figures 1 and 2, the engine comprises a working cylinder 11 set with its axis vertical, a crank-shaft 12 below the cylinder and a transverse half-time shaft 13 beyond the cylinder. There is also an intermediate half-time shaft 14 at one side of the cylinder.

In the cylinder is a thin steel sleeve-valve 15 which is long enough to project beyond the cylinder-bore at both ends and which is operated by means hereinafter described from the intermediate half-time shaft 14. Within the sleeve-valve there is a main piston 16 and a connecting rod 17^a extends from the main piston to the crank-shaft 12. Above the main piston is an auxiliary head-piston 17 operatively connected to a crank 18 on the half-time shaft 13 above the cylinder, by a short connecting-rod 19. The operative connections of the head-piston 17 are such that this approaches the main piston 16 as closely as possible once in every two complete reciprocations of the main piston when the latter is at the inner end of its stroke. The parts are shown in this position in Figure 1. In the head-piston there is carried a spark-plug 20 for ignition of an explosive charge.

The lower edge of the head-piston is constituted by a junk-ring 21 which acts as a fluid-tight packing and an obturating-lip. An exhaust-port 22 is cut through the cylinder-walls at a transverse plane across the cylinder which lies just above the plane at which the head-piston and the main-piston most closely approach one another. This exhaust-port is continuous around the cylinder-wall. Below the exhaust-port is a narrow "land" 23 and below the "land" is a peripheral inlet-port 24.

The sleeve-valve is ported at 25 around its whole periphery, the port being interrupted by transverse vertical ribs 26 at intervals which serve to unite the upper and lower parts of the valve and to provide a bearing-surface for the pistons. The vertical width of the sleeve-valve port 25 is equal to the vertical width of "land" 23 between the inlet and exhaust-ports.

An eccentric cam or cams 27 upon the intermediate half-time shaft 14 serve to actuate the sleeve-valve 15. A rocking-lever 28 is located below the intermediate half-time shaft 14 and one arm of this lever extends towards the sleeve-valve 15 and is forked into two branches 29. Each branch carries a slide-way and in the slideway works a slide-block 30. The slide-blocks are bored transversely at 31 to engage operating-pins 32 which project laterally outward from the wall of the sleeve-valve at its lower end, where it projects below the bottom edge of the cylinder-wall. The rocking-lever 28 has also two upward branches 33, 34 which extend on opposite sides of the cams 27 on the intermediate half-time shaft. Only one of these cams is shown, in dotted lines, in Figure 1. One branch 34 carries a cam-roller 35 to engage one of the cams and the other a cam-roller 36 to engage the other cam. By properly proportioning the cams they are caused to impart positive

up and down movement free of back-lash to the sleeve-valve 15.

The upper half-time shaft 13 which operates the head-piston 17 is enclosed within a suitable casing 37 and an air-inlet door 38 is provided in the casing on one side. An outlet opening 39 is provided on the other side of the casing 37, and is connected to the inlet of a carburetor (not shown). The outlet of the carburetor is connected to the inlet-port 24 of the engine, as indicated by the chain line 40, Figure 1. In this way air is drawn through above the movable head-piston 17 and is preheated before passing to the engine. The rest of the engine, i. e. the cylinder-walls, are water-jacketed as shown both over the working part of the walls and also over the portion which extends around the periphery of the head-piston.

The timing and location of the sleeve-valve and the head-piston in relation to the main piston is such as is indicated diagrammatically in Figure 2, according to which when the main piston reaches the top of its stroke and the head-piston is close to the main piston, the sleeve-valve port is opposite the "land" between the inlet and exhaust-ports.

In the diagram, Figure 2, horizontal measurements represent time and the chain lines A, B, C and D represent the times in the course of the working cycle at which the main piston comes to one of its dead centres. A and C correspond to the times of two outer dead centres and B and D to the times of two inner dead centres of the main piston.

Vertical measurements represent distances measured axially along the cylinder. The horizontal line *a* represents the height of the upper edge of the exhaust-port 22, the horizontal line *b* corresponding to the lower edge of the said port. The horizontal line *c* corresponds to the upper edge of the inlet-port and *d* to the lower edge of the said port. Thus the space *b*, *c* corresponds to the "land" between the inlet and the exhaust ports. The movement of the lower edge of the sleeve-valve port is indicated by the full line I and the movement of the lower edge of the obturating lip, formed by the junk-ring 21 on the head-piston is indicated by the full line II. The movement of the upper edge of the sleeve-valve port is indicated for a short distance at I^a.

On study of the diagram it will be seen that this begins on the left-hand side somewhat before the main-piston reaches its outer dead-centre corresponding to the line A. The curve I is below the curve II, indicating that the lower edge of the sleeve-valve port is below the bottom of the head-piston, and as it is opposite the space between the lines *c*, *d*, representing the inlet-port, it will be seen that this port is open. The main-piston in moving forward is therefore drawing in a charge. This condition of affairs con-

tinties somewhat beyond the outer dead-centre at A. A little beyond the dead-centre, however, the port in the sleeve-valve in rising passes above the inlet-port and the bottom of the head-piston. The charge is thereby shut into the working space and compression begins at E. Since the lower edge of the sleeve-valve port passes above the obturating-lip of the head-piston (as is indicated by the curves I and II crossing one another) at the same time that the sleeve-valve closes the inlet-port, the pressure is held between the main piston, the head-piston and the unported portion of the interior 10 of the sleeve-valve. There is therefore no possibility of leakage except past the pistons, which can be properly packed to prevent such leakage. Moreover, the sleeve-valve by this movement rises above the 15 "land" 23 and comes opposite the exhaust-port 22 in readiness for this port to be 20 opened by the obturating-lip (curve II) at a later stage.

It will be noted that during the compression stroke the head-piston (curve II) rises above the level of the exhaust-port (shown by lines a, b). The compression space is, however, still closed as the sleeve-valve port (curve I) has moved upwardly further still 25 and lies above the obturating-lip on the head-piston. The upward movement of the head-piston ensures that at the inner dead centre of the main piston (line E) there is a suitable compression space between the two pistons. 30 At, or slightly before, this position the charge is fired by means of the sparkling-plug.

Outward movement of the main piston takes place from the time B onward. The 35 head-piston is still rising and both pistons therefore allow for expansion of the charge. A considerably greater expansion ratio is thereby obtained than is possible in an engine having only one working piston.

During the expansion stroke the sleeve-valve commences to move downwardly and at the time F its lower edge passes below the bottom of the head-piston and thereby opens the exhaust port. This takes place shortly 40 before the second outer dead centre (time C) of the main piston. While the main piston is returning, between the times C and D the sleeve-valve and the head-piston move downwardly as can be seen from the curves I and II and the exhaust-port remains open. At the second inner dead centre of the main piston, time D, the head-piston has moved downwardly so that it approaches the main 45 piston closely. The point of closest approach is just beyond the dead centre at G and the port in the sleeve-valve is arranged to coincide with the "land" between the inlet and exhaust ports at this instant, as will be seen from the curves I and I^a. The exhaust-port 50 is thereby closed and further movement of

the parts causes the main-piston to recede from its inner dead-centre and the sleeve-valve to open the inlet-port. The inlet-stroke then again commences.

The shape of the curve I which represents the successive positions of the inlet-port lower edge is not in the diagram a strict sine curve, and the cams 27, Figure 1, are so shaped as to impart this peculiar movement to the sleeve-valve. It is quite possible, however, to cause the ports to open and close correctly with the sleeve-valve which is given a simple harmonic motion (which would appear as a sine curve in the diagram) at the expense of not securing quite so large an overlap between the head-piston of the port during the compression and expansion strokes. If the sleeve-valve is to be given an approximately simple harmonic motion, then instead of the cams 27 and rocker 28 a simple eccentric device may be employed for actuating it from the half-time shaft 14.

Referring now to the multi-cylinder construction illustrated in Figures 3 to 5, the main piston 16, sleeve-valve 15, head-piston 17 and exhaust and inlet-ports 22, 24, remain substantially as hereinbefore described. Moreover the relative movement of the parts is the same. The intermediate half-time shaft 14 is, however, dispensed with and the operative connections for actuating the sleeve-valve 15 receive their motion from the upper half-time shaft or cam-shaft 18.

The cam-shaft 18 carries two eccentrics 50 on which work roller-bearing eccentric-sheaves 51 forming part of eccentric-rods 19. The eccentric-rods 19 work upon a gudgeon-pin 52 on the head-piston 17. In the construction illustrated in Figures 3 and 5 the head-piston comprises two end sections 53, 54 of cylindrical shape which fit the bore of the sleeve-valve and are united by a central waist 55. The gudgeon-pin 52 is located between ears 56 in the upper part of the head-piston. The sparking-plug 20 fits diagonally 50 in the side of the waist of the head-piston and communicates with the working space of the cylinder by means of a short axial bore 57. To accommodate the sparking-plug, which projects beyond the bore of the cylinder laterally, a port 58 is cut in the side of the sleeve-valve and this is made long enough to accommodate the sparking-plug notwithstanding the relative movement between the sleeve-valve and the head-piston. An air-passage 59 enters the side of the cylinder opposite the port 58 and the sparking-plug projects into the air-passage.

On the opposite side of the head-piston the sleeve-valve 22 is provided with another air-port 60, which like the air-port 58 is in constant communication with the space formed by the waist of the head-piston. An air-passage 61 is pierced through the cylinder-wall opposite the port 60. The air-passage 62

61 is connected to a manifold 62 which is in communication with the air-passages of all the cylinders of the engine. The manifold 62 is connected to a carburettor (not shown) 5 and the outlet from the carburettor to a second manifold 63 which distributes the mixture to the inlet-ports 24 of the cylinders of the engine. Over the air-port 59 in the cylinder-wall is a gauze 64 which carries an insulated terminal 65 coupled by a spring 66 to the sparking-plug 20.

On the gudgeon-pin 52 and between the eccentric-rods 19 there is pivoted a sleeve-valve actuating-rocker 67. This rocker has an arm 15 which extends laterally beyond the head-piston and terminates in an eccentric sheave 68. Within this sheave is an eccentric 69 formed in one piece with a rocking-pin 70. The rocking-pin 70 is journalled in ears 71 which project laterally from the top of the sleeve-valve 22. Thus when the rocker 67 is turned about its pivot on the gudgeon-pin 52 of the head-piston, the sleeve-valve 22 will be raised or lowered relatively to the head-piston.

25 The rocker 67 has two arms 72, 73 which extend upwardly one on either side of the cam-shaft 18 and carry pallets 74, 75, which face inwardly toward the shaft. The shaft is provided with cams 76, 77 one of which engages each of the pallets 74, 75, as shown in Figure 3. Thus the cam 76 pressing on the pallet 74 tends to move the rocker 67 to the left while the cam 77 pressing on the pallet 75 tends to move it to the right, when viewed 30 in the position illustrated in Figure 3. The cams 76, 77 are so shaped that the movement they impart to the rocker 67 superimposes upon the sleeve 72, a movement additional to that of the head-piston 17, sufficient to bring 35 about a motion substantially in accord with curve I, Figure 2.

To provide for lubrication of the parts an oil-pipe 80 extends along the top of the interior of the casing 37 and is provided with 45 openings at suitable intervals. Oil propelled through the pipe by a lubricating pump on the engine therefore drips on to the cams and eccentrics of the cam-shaft 18, as well as on to the bearings thereof and it is thrown by 50 the movement of the parts into all the working-joints. A gutter 81 is formed round the upper end of each cylinder-bore and directs the oil into a drainage pipe 82 from which it is directed into a casing 83 surrounding the 55 driving-gear 84 over the cam-shaft 18. In this casing it descends to the engine crank-case. It is to be observed that by the construction described the upper section 54 of the head-piston prevents excess of lubricating 60 oil from accumulating upon the sparking-plug 20 and also from admixture with the incoming air for the carburetor. At the same time the air entering through the passage 29 helps to keep the head-piston and associated 65 parts cool and is itself somewhat preheated.

A further detail to which attention may be directed is that the eccentric sheaves 51 are each in a single piece and their diameter is slightly greater than the largest diameter of the cam-shaft 18, so that they may be 70 passed over the cam-shaft in assembling the parts. The sheaves are held in place over the roller-bearings by means of plates 78 each in two halves which are secured to the ears on the sheaves by set-screws 79. The 75 plates enter grooves in the cam-shaft shown at 85 and they also serve to retain the rollers 86 in place. Between the rocker 67 and gudgeon-pin 52 a roller-bearing is inserted and rollers are also placed between the sheave 80 88 and eccentric 69.

The arrangement of the water-cooling jacket around the cylinder and the inlet and exhaust-ports can be readily effected in the construction described. Figure 5 shows a 85 cross-section through the cylinder-plug at the level of the exhaust-port and it will be seen that each of the exhaust-ports is nearly surrounded by a water-space 90 taken in conjunction with water-passages 91 which divide 90 the individual exhaust-passages 92 of each cylinder from one another. In Figure 5 the cylinder-wall is represented at 11 and it will be seen that the exhaust-port extends all round this wall and is not interrupted at the 95 wall by any transverse ribs. Thus the exhaust passage may be produced by cutting straight through the cylinder-wall on a suitable machine-tool and this facilitates its exact location. A cast passage would not be 100 equally satisfactory. The same applies to the manufacture of the inlet-port in the cylinder-wall. In order to prevent exhaust-gases from one cylinder impinging upon the outside of the sleeve-valve of the adjacent cylinder at the moment when the exhaust-port is 105 opened, the exhaust spaces of each cylinder are completely divided from one another by intermediate ribs 93.

Figures 6 and 7 show a modified form of 110 sleeve-valve actuating rocker 67. In this case the pallets 74, 75 are provided upon adjustable wedge-shaped pallet-blocks 94, 95. The pallet-blocks are bolted to divergent slots 96, 97 on the arms 72, 73 of the rocker 115 and by sliding them up and down their distance apart may be adjusted so as to take up any back-lash which otherwise might exist between the cams 76, 77 and the pallets. It will be understood that the cams 76, 77 are 120 complementary in shape so that back-lash is equally avoided in all positions of the cams.

We claim:—

1. An internal-combustion engine comprising in combination a cylinder, a sleeve-valve 125 therein, a main piston and head-piston within the sleeve-valve, means for reciprocating the pistons so that the head-piston approaches the main-piston closely once in each two complete reciprocations of the main-piston, a 130

rocker pivoted upon the head-piston and operatively connected to the sleeve-valve a transverse "half-time" shaft beyond the head-piston and operative connections between the 5 rocker and the transverse "half-time" shaft.

2. An internal combustion engine comprising in combination a cylinder, a sleeve-valve therein, a main-piston and head-piston within the sleeve-valve, means for reciprocating the 10 main piston, a transverse "half-time" shaft beyond the head-piston, means thereon for reciprocating the head-piston, a rocker pivoted upon the head-piston and operatively connected to the sleeve-valve and means for actuating the rocker comprising operative connections to the said transverse "half-time" shaft.

3. An internal-combustion engine of the type described as claimed in claim 2 wherein 20 the operative connections between the transverse shaft and the rocker comprise pallets upon the rocker extending one on either side of the transverse shaft and cams upon the shaft to engage said pallets.

25 4. An internal-combustion engine of the type described as claimed in claim 2 wherein in the operative connections between the transverse shaft and the rocker comprise pallets upon the rocker extending one on either 30 side of the transverse shaft and cams upon the shaft to engage said pallets, the said pallets being adjustably mounted upon the rocker as to their distance apart, for the purpose described.

35 5. In an internal combustion engine the combination of a working cylinder provided with inlet and exhaust ports in the cylinder wall situated close together and separated by a "land" of small dimensions, a main-piston 40 therein, a connecting rod and crank shaft operatively connected therewith, a sleeve-valve interposed between the cylinder-bore and the main piston, a port in the sleeve-valve, means to impart to and fro motion to the sleeve 45 valve across the said "land" so that the port in the sleeve valve alternately opens the inlet or the exhaust ports, a movable head piston within the cylinder and sleeve valve, means to cause the head piston to approach the main 50 piston closely at the end of the exhaust stroke and an obturating lip on the head piston so located as to shut off the port in the sleeve-valve from the working space between the 55 pistons when the parts are in a position which when the engine is running will involve high-pressure in the working space.

6. In an internal combustion engine, the combination with a ported sleeve valve, of a 60 cylinder provided with inlet and exhaust ports situated close together and separated by a "land" of small dimensions in the direction of travel of the sleeve valve, means to actuate the sleeve valve so that the port therein alternately opens the inlet and exhaust ports

in the cylinder wall, a head piston having an obturating lip within the sleeve valve so located as to shut off the port in the sleeve valve from the working space between the pistons when the parts are in a position which when the engine is running will involve high pressure in the cylinder. 70

7. In an internal combustion engine, the combination with a ported sleeve valve, of a cylinder provided with inlet and exhaust ports situated close together and separated by a "land" of small dimensions in the direction of travel of the sleeve valve, means to actuate the sleeve valve so that the port therein alternately opens the inlet and exhaust ports 75 the cylinder wall, a head piston formed with a central waist, the surrounding sleeve being provided with a port opposite to the waist, said waist and port serving to accommodate a sparking plug. 80

8. In an internal combustion engine, the combination with a ported sleeve valve, of a cylinder provided with inlet and exhaust ports situated close together and separated by a "land" of small dimensions in the direction of travel of the sleeve valve, means to actuate the sleeve valve so that the port therein alternately opens the inlet and exhaust ports in the cylinder wall, a head piston having a central waist, said sleeve valve being ported 90 at two places opposite the waist in the head piston, and a gas passage entering the cylinder opposite one of the said ports and leaving it opposite the other of the said ports. 95

In testimony whereof we have signed our names to this specification. 100
